Patented Mar. 29, 1921.

UNITED STATES PATENT OFFICE.

EARL H. SINGERS, OF HELTONVILLE, AND ROY LOFFLAND, OF WORTHINGTON,
INDIANA, ASSIGNEES TO CEMENT PRODUCTS COMPANY, OF WORTHINGTON,
INDIANA, A CORPORATION OF INDIANA.

SILO.

1,372,837.

Specification of Letters Patent. Patented Mar. 29, 1921.

Application filed June 9, 1915. Serial No. 33,082.

To all whom it may concern:

Be it known that we, EARL H. SINGERS and ROY LOFFLAND, citizens of the United States, residing at Heltonville and Worthington, in the counties of Lawrence and Greene and State of Indiana, respectively, have invented certain new and useful Improvements in Silos, of which the following is a specification, reference being had 10 therein to the accompanying drawing.

This invention relates to certain new and useful improvements in silos; the object being to provide a silo which is formed of interlocking double tongued and grooved 15 cement staves arranged with break-joints in such a manner, that the staves at their abutting edges are interlocked so as to form a very strong and durable silo, and at the same time a tight joint is formed so as to 20 exclude air and moisture.

Another object of the invention is to provide a silo which is formed of staves provided with acute angled edges each edge having a pair of grooves and a pair of 25 tongues which are adapted to interlock with the abutting edge of the adjacent stave, the angle of the edges of the respective staves, determining the diameter of the 30 complete silo whereby by changing the angle of the edges of the staves, silos of various diameters can be formed.

Another object of the invention is to provide a stave silo in which the staves are provided with flat faces in order to reduce the 35 cost of manufacturing the same.

Another object of the invention is to provide a silo in which the door frames are formed of cement blocks reinforced in such a manner that exceedingly strong and durable frames are formed; the side edges of 40 which are also provided with double tongues and grooves interlocking with the grooves and tongues of the adjacent staves.

A still further object of the invention is 45 to provide a stave silo in which the staves are interlocked and held rigid in position, without the use of mortar.

Other and further objects and advantages of the invention will be hereinafter set forth 50 and the novel features thereof defined by the appended claim.

In the drawings—

Figure 1, is a vertical section through a portion of a silo showing the manner of con-

structing the same according to our improved invention;

Fig. 2, is an enlarged horizontal section through a portion of a silo showing the manner of constructing the door frames and doors therefor;

Fig. 3, is a perspective of a portion of a silo showing the door frame in position in respect to the abutting staves and the manner of fastening the door within the frame; and

Fig. 4, is a detail elevation showing the manner of fastennig the hoops.

Like numerals of reference refer to like parts in the several figures of the drawings.

In constructing a silo in accordance with our invention, a circular base of concrete is formed in the bottom of an excavation approximately fifteen inches wide and with the upper surface thereof thirty-six inches 75 below the surrounding ground, the circular opening formed by said base being provided with a cement bottom.

Upon the center of this foundation 1, a row of staves 2 and 3 of alternate lengths 80 approximately one and one-half feet and three feet respectively, is placed on the edge forming the base row of staves, these staves being formed with acute angled edges, each stave having on its edge, a pair of tongues 85 4 and a pair of grooves 5 into which the tongues of the adjacent staves are adapted to interlock so as to form a tight joint and it will be seen that by forming staves with different angles, silos of different diameters 90 can be constructed.

These staves are formed approximately twelve inches wide and upon the first row of staves, an additional row of staves all of the same length, is placed so that when the 95 complete silo is formed, the top and bottom rows of staves constituting the same will be formed of alternating lengths of staves and the intermediate staves will be all of the same length, whereby a silo is formed with 100 break-joints.

Arranged on the base or foundation, is a flat spacer block approximately thirty-six inches square and three inches thick, which extends to the ground level and forms 105 a closure for the door frame opening which is arranged in the silo when the same is being constructed and into which is placed a

series of superposed door frames 6 which are reinforced by square reinforcing rods 7 and are provided with double tongues and grooves along their edges which interlock 5 with the grooves and tongues of the abutting staves. The flat spacer blocks are provided with acute angled edges having tongues and grooves on its edges interlocked with the adjacent staves to form a complete 10 closure at the base of the silo.

These door frames are provided with rabbeted walls adapted to receive reinforced doors 8, said doors being reinforced by square rods 9 embedded therein when the 15 same are being constructed and each door is provided with a reinforcing plate 10 carrying a threaded stud 11 on the end of which is mounted a fastening bar 12 secured in position thereon by a nut 13 said 20 bar being adapted to engage the outer faces of the door frame when swung into the positions shown in Figs. 2 and 3, in order to securely fasten the doors within the frames so as to form a tight joint, and it 25 will be seen that these fastening members or bars can be swung into such a position that the doors can be removed from the side of the silo as the silage is removed therefrom.

30 At intervals, circular hoops 14 are placed around the silo thus formed, the ends of said hoops being threaded and extending through castings 15 and are provided with nuts 16 for placing said hoops under tension 35 so as to hold the staves firmly in position.

The inner face of the silo is then brushed with an acid-resisting cement so as to completely close all of the cracks, although we 40 have found that in constructing a silo in accordance with our invention, the joints between the abutting sections form complete closures at that point so as to exclude air and moisture without the use of this additional inner coating and, therefore, we 45 do not wish to limit ourselves to the use of such a coating as the silo can be constructed and used to good advantage, without such a coating.

50 From the foregoing description, it will be seen that we have provided a silo in which the staves are interlocked at the abutting

edges thereof in such a manner that an exceedingly strong and durable silo is formed and one which can be readily assembled or taken apart, the weight of the superposed staves compressing the abutting upper and lower edges of the staves together in such a manner that an exceedingly tight joint at this point, is also formed. 60

It will be seen that by the construction of the silo as herein shown and described in connection with the door construction, the doors are interchangeable and can be securely fastened in the door frames or within the vertical door opening in case the silo is constructed without a door frame. 65

We claim:

A built-up circular silo comprising a circular concrete base embedded in the ground 70 below the surface thereof, a plurality of flat staves of alternate length, arranged on said base, having horizontally disposed upper and lower edges and acute angled side edges, each stave having on its angled edge 75 a pair of tongues and a pair of grooves, adapted to interlock with one another, a series of rows of similar constructed staves all of the same length, arranged above the first mentioned row to form break joints 80 between the respective staves, a flat spacer block having acute angled edges, provided with tongues and grooves arranged on said base, having its edges interlocked with the adjacent staves, a plurality of superposed 85 flat door frames having horizontally disposed upper and lower edges, and acute angled side edges provided with spaced tongues and grooves, arranged on said spacer block, having their edges interlock 90 with the tongues and grooves of the adjacent staves, the upper and lower edges of the door frames being out of horizontal alignment with the upper and lower edges 95 of the staves, and circular hoops arranged around said staves and door frames.

In testimony whereof we hereunto affix our signatures in the presence of two witnesses.

EARL H. SINGERS.
ROY LOFFLAND.

Witnesses:

RUSSELL G. EAST,
JOSEPH Housum.
